ABSTRACT

A pulsatile fluid pump apparatus includes an integral pump assembly employing a flexible diaphragm in a diaphragm assembly; a pulsatile fluid pump system including a control housing, for removably receiving the integral pump assembly, the control housing and the integral pump assembly being configured for operation, in a first mode, so that the pulsatile fluid pump system reciprocally actuates the diaphragm assembly to cause pumping automatically; and a manual driver assembly, wherein the integral pump assembly is configured, in a second mode, in the absence of actuation of the diaphragm assembly by the pulsatile fluid pump system, to removably receive the manual driver assembly to support manual actuation and operation of the diaphragm assembly.

MANUAL DRIVER ASSEMBLY FOR A PULSATILE FLUID PUMP

TECHNICAL FIELD

The present invention relates to pulsatile fluid pumps, and more particularly to pulsatile fluid pumps suitable for pumping blood.

BACKGROUND ART

A pulsatile fluid pump is taught in U.S. Pat. No. 7,850,593 ("our prior patent") for an invention of Douglas Vincent and Matthew Murphy; Douglas Vincent is a co-inventor of the present invention. Our prior patent discloses a pump actuated by a linear motor configured to cause reciprocation of a flexible membrane, serving as a wall of a fluid housing, that is in turn coupled to a pair of ball valves, in a manner as to implement pulsatile fluid flow.

The present application is related to four applications bearing U.S. patent application Ser. Nos. 17/182,915, 17/182,893, 17/183,067, and 17/183,080, respectively. Each of these related applications is hereby incorporated herein by reference in its entirety.

SUMMARY OF THE EMBODIMENTS

In accordance with one embodiment of the invention, a pulsatile fluid pump apparatus includes an integral pump assembly employing a flexible diaphragm in a diaphragm assembly; a pulsatile fluid pump system including a control housing, for removably receiving the integral pump assembly, the control housing and the integral pump assembly being configured for operation, in a first mode, so that the pulsatile fluid pump system reciprocally actuates the diaphragm assembly to cause pumping automatically; and a manual driver assembly, wherein the integral pump assembly is configured, in a second mode, in the absence of actuation of the diaphragm assembly by the pulsatile fluid pump system, to removably receive the manual driver assembly to support manual actuation and operation of the diaphragm assembly.

Alternatively or in addition, the integral pump assembly is configured to operate in any spatial orientation. Also alternatively or in addition, for operation in the first mode, the diaphragm assembly has a normal orientation in the control housing so as to be in contact with a pushrod assembly to cause reciprocation of the flexible diaphragm.

Further alternatively or in addition, the integral pump assembly is configured to slide into and out of the control housing. Alternatively or in addition, the integral pump assembly is configured, in the second mode, to be in an inverted orientation in the control housing relative to the normal orientation of the diaphragm assembly, so as to expose the diaphragm assembly for convenient attachment of the manual driver assembly. In the second mode, the pulsatile fluid pump system is not operationally connected to the integral pump assembly and therefore does not cause reciprocation of the diaphragm assembly.

Alternatively or in addition, the control housing is configured to receive and hold the integral pump assembly in the inverted orientation. Also alternatively or in addition, the manual driver assembly includes an arm configured to be pivotally mounted to a housing of the integral pump assembly, and the arm is coupled to a handle having a foot that reciprocally moves the diaphragm assembly when the handle is pumped.

Alternatively or in addition, the manual driver assembly includes a stroke volume limiter, disposed between the handle and the foot, and configured to limit, by an adjustable amount, a change in stroke volume effectuated by the manual driver assembly. Also alternatively or in addition, the stroke volume limiter defines a plurality of notched orientations, each orientation establishing a distinct limit on travel of the manual driver assembly.

Further alternatively or in addition, the pulsatile fluid pump system has an integral storage location for stowing the manual driver assembly when it is not being used.

In accordance with a related embodiment of the invention, the manual driver assembly is a knob assembly.

BRIEF DESCRIPTION OF THE DRAWINGS

The foregoing features of embodiments will be more readily understood by reference to the following detailed description, taken with reference to the accompanying drawings, in which:

FIG. 1 is a side perspective view of a pulsatile fluid pump apparatus 300 comprised of a pulsatile fluid pump system 301, integral pump assembly 200 and manual driver assembly 600, in accordance with an embodiment of the present invention.

FIG. 2 is a similar side perspective view of the pulsatile fluid pump apparatus 300 of FIG. 1 showing the manual driver assembly 600 stowed in the manual driver storage 381.

FIG. 3 is a side view of the pulsatile fluid pump apparatus 300 showing the manual driver assembly 600 removed from the manual driver storage 381 with the integral pump assembly 200 placed in the manual operating position.

FIG. 4A is a closeup of the manual driver assembly 600 showing a stroke volume limiter 621 having three stroke volume limit settings.

FIG. 4B shows the manual driver assembly 600 of FIG. 4A with a cutaway interior view of the stroke volume limiter 621 set to the smallest stroke volume setting.

FIG. 4C shows the manual driver assembly 600 of FIG. 4A with a cutaway interior view of the stroke volume limiter 621 set to an intermediate stroke volume setting.

FIG. 4D shows the manual driver assembly 600 of FIG. 4A with a cutaway interior view of the stroke volume limiter 621 set to the largest stroke volume setting.

FIGS. 5A-D show successive actions used to attach the manual driver assembly 600 of FIG. 1 to the integral pump housing 200.

FIG. 6A is a cutaway interior perspective view of the manual driver assembly 600.

FIG. 6B shows the manual driver assembly 600 with a cutaway interior view of the stroke volume limiter 621.

FIGS. 7A-D & 8A-D show operation of the manual driver assembly in a pumping sequence and of the stroke volume limiter 621.

FIGS. 7A-D are side perspective views of the pulsatile fluid pump apparatus 300 showing the manual driver assembly 600 attached to the integral pump assembly 200, which is mounted in the pulsatile fluid pump system 301 in the manual operating position.

FIG. 7A shows the handle in the full up, or diastole, position with the stroke volume limiter 621 shown in the largest stroke volume limit position.

FIG. 7B shows the handle in the full down, or systole, position with the stroke volume limiter 621 shown in the largest stroke volume limit position.

FIG. 7C is similar to FIG. 7A except the stroke volume limiter 621 is shown in the smallest stroke volume limit position.

FIG. 7D is similar to FIG. 7B except the stroke volume limiter 621 is shown in the smallest stroke volume limit position.

FIGS. 8A-D are views of the manual driver assembly 600 attached to the integral pump assembly 200 (for clarity, shown outside of the pulsatile fluid pump system 301) in the manual operating position.

FIG. 8A is a cutaway interior view of the manual driver assembly 600 attached to a vertical section of the integral pump assembly 200 in manual orientation in the diastole mode, with the stroke volume limiter 621 in the largest setting.

FIG. 8B is a cutaway interior view of the manual driver assembly 600 attached to a vertical section of the integral pump assembly 200 in manual orientation, midway between the full diastole and full systole positions, with the stroke volume limiter 621 in the largest setting.

FIG. 8C is a cutaway interior view of the manual driver assembly 600 attached to a vertical section of the integral pump assembly 200 in manual orientation, in the systole mode, with the stroke volume limiter 621 in the largest setting.

FIG. 8D is a view of the manual driver assembly 600 attached to a vertical section of the integral pump assembly 200 in manual orientation, in the systole mode, with the stroke volume limiter 621 in the smallest setting.

FIG. 9 shows the graphic display 400 mounted in the pulsatile fluid pump 301.

FIG. 10 shows typical operation of the graphic display 400.

FIG. 11A is a vertical section of the pulsatile fluid pump apparatus 300 of FIG. 1 including the pulsatile fluid pump system 301 and the integral pump assembly 200 in the normal operating mode.

FIG. 11B is a vertical section of the pulsatile fluid pump apparatus 300 of FIG. 1 including the pulsatile fluid pump system 301 and the integral pump assembly 200 in the manual operating mode. The manual driver assembly 600 is shown attached to the integral pump assembly 200.

FIGS. 12A-D show a second embodiment of a manual driver assembly in accordance with the present invention.

FIG. 12A shows a perspective view of the manual driver knob assembly 690 in accordance with an embodiment of the present invention.

FIG. 12B shows a front view of the manual driver knob assembly 690 of FIG. 12A.

FIG. 12C shows the manual driver knob assembly 690 of FIG. 12A, immediately prior to attachment to the diaphragm assembly 201 via the coupler slot 214a.

FIG. 12D shows the manual driver knob assembly 690 of FIG. 12A after attachment to the diaphragm assembly 201 via the coupler slot 214a, ready for manual pumping.

DETAILED DESCRIPTION OF SPECIFIC EMBODIMENTS

Definitions. As used in this description and the accompanying claims, the following terms shall have the meanings indicated, unless the context otherwise requires:

“Diastole mode” is a phase of operation of a pulsatile pump, according to embodiments of the present invention, during which the diaphragm 202 (not shown) of the pump-valving assembly 101 (not shown) is pulled away from the

chamber 102 (not shown) so as to create negative pressure within the chamber 102 (not shown).

“Systole mode” is a phase of operation of a pulsatile pump, according to embodiments of the present invention, during which the diaphragm 202 (not shown) is pushed towards the chamber 102 (not shown), so as to create positive pressure within the chamber 102 (not shown).

“Normal operating position” is when the integral pump assembly 200 is inserted into the pulsatile fluid pump system 301 with the coupler slot 214a in a downwards orientation such that the coupler slot 214a engages with push rod 342 (not shown) for normal, automated operation.

“Manual operating position” is when the integral pump assembly 200 is inserted into the pulsatile fluid pump system 301 with the coupler slot 214a facing in an upwards orientation so that the manual driver assembly 600 may be attached to the integral pump housing 200 by hooking the pump housing engagement pin 602 into the pump housing manual driver notch 222 as shown in FIG. 5B.

A “set” includes at least one member.

The term “physical flow characteristic” includes a measured attribute such as stroke strength, beat rate, flow rate, average flow rate 411a, stroke volume 411b, flow index 411c, pulse pressure, flow rate waveform 412, and stroke volume waveform 413, as well as combinations of any of the foregoing attributes.

The manual driver assembly 600 is a component of a pulsatile fluid pump system 301 in accordance with an embodiment of the present invention.

FIG. 1 is a side perspective view of a pulsatile fluid pump apparatus 300 including a pulsatile fluid pump system 301, integral pump assembly 200 and manual driver assembly 600, in accordance with an embodiment of the present invention. The pulsatile fluid pump system 301 has an enclosure 380 containing, among other things, manual driver storage 381. The manual driver storage 381 is identified by side labeling 382 and corner labeling 383 to aid the operator in identifying and locating the manual driver assembly 600. The integral pump assembly 200 contains, among other things, a coupler 214 with coupler slot 214a, a pump housing 221, and a pump housing manual driver notch 222. (In these figures, like numbered items correspond to similar components across different figures and across the applications bearing U.S. patent application Ser. Nos. 17/182,915, 17/182,893, 17/183,067, and 17/183,080)

FIG. 2 is a similar side perspective view of the pulsatile fluid pump apparatus 300 of FIG. 1, showing the manual driver assembly 600 stowed in the manual driver storage 381. This arrangement allows the manual driver to be visible and immediately available to the operator in case it is needed. The integral pump assembly 200 is shown in the normal operating position, where the integral pump assembly 200 is inserted into the pulsatile fluid pump system 301 with the coupler slot 214a (shown in FIG. 1) in a downwards orientation such that the coupler slot 214a (shown in FIG. 1) engages with push rod 342 (shown in FIGS. 12A-B).

FIG. 3 is a side view of the pulsatile fluid pump apparatus 300 showing the manual driver assembly 600 removed from the manual driver storage 381. The integral pump assembly 200 is shown in the manual operating position—accomplished by removing the integral pump assembly 200 from the pulsatile fluid pump system 301, flipping it upside down, then re-inserting it back into the pulsatile fluid pump system 301 with the coupler slot 214a facing in an upwards orientation so that the manual driver assembly 600 may be attached to the integral pump housing 200. Should the pulsatile fluid pump system 301 once again become opera-

tional, the integral pump assembly 200 may once again be removed from the pulsatile fluid pump system 301, then re-inserted back into the pulsatile fluid pump system 301 in the normal operating position and the manual driver assembly 600 returned to manual driver storage 381.

FIG. 4A is a closeup of the manual driver assembly 600 showing a stroke volume limiter 621 having three stroke volume limit settings: smallest (indicated by the small stroke volume limit indicator window 623a), intermediate (indicated by the medium stroke volume limit indicator window 624a), and largest (indicated by the large stroke volume limit indicator window 625a) stroke volume limit, guiding the operator to deliver the desired stroke volume to the patient. While three stroke volume limit settings are disclosed herein, it is expressly contemplated that the stroke volume limiter may have less than three stroke volume limit settings or more than three stroke volume limit settings. Once removed from manual driver storage 381 (shown in FIG. 1), the manual driver assembly 600 is adjusted to the desired stroke limit setting (as indicated by the corresponding stroke volume limit indicator window 623a, 624a, 625a) by adjusting the stroke volume limiter 621. This is accomplished by pulling on the stroke volume limiter finger grip 622 to cause the stroke volume limiter 621 to cause the stroke volume limiter pin 613 to compress the stroke volume limiter spring 614 (shown in FIGS. 4B-D). With the stroke volume limiter spring 614 (shown in FIGS. 4B-D) compressed, the stroke volume limiter 621 may be rotated around the stroke volume limiter pin 613 such that the stroke volume limiter protrusion 615 (shown in FIGS. 4B-D) engages with one of three stroke volume limit notches (small stroke volume limit notch 623b [shown in FIGS. 4B-D], medium stroke volume limit notch 624b [shown in FIGS. 4B-D], or large stroke volume limit notch 625b [shown in FIGS. 4B-D]) when the stroke volume limiter 621 is released. The selected stroke volume limit indicator 626 is a contrasting color that shows through the selected stroke volume limit indicator window 623a, 624a, 625a. The stroke volume limit setting may be changed at any time.

FIG. 4B is a cutaway view of the manual driver assembly 600 of FIG. 4A that shows the stroke volume limiter 621 set to the smallest stroke volume setting as the stroke volume limiter protrusion 615 is shown engaged with the small stroke volume limit notch 623b. In this position, the stroke volume limit indicator 626 is visible through the small stroke volume limit indicator window 623a (shown in FIG. 4A).

FIG. 4C is a cutaway view of the manual driver assembly 600 of FIG. 4A that shows the stroke volume limiter 621 set to the intermediate stroke volume setting as the stroke volume limiter protrusion 615 is shown engaged with the medium stroke volume limit notch 624b. In this position, the stroke volume limit indicator 626 is visible through the medium stroke volume limit indicator window 624a (shown in FIG. 4A).

FIG. 4D is a cutaway view of the manual driver assembly 600 of FIG. 4A that shows the stroke volume limiter 621 set to the largest stroke volume setting as the stroke volume limiter protrusion 615 is shown engaged with the large stroke volume limit notch 625b. In this position, the stroke volume limit indicator 626 is visible through the large stroke volume limit indicator window 625a (shown in FIG. 4A).

FIGS. 5A-D shows successive actions used to attach the manual driver assembly 600 of FIG. 1 to the integral pump housing 200. As shown in FIG. 5A, the coupler slot 214a is in the manual operating position so that the manual driver assembly 600 may be attached to the integral pump housing

200. FIG. 5B shows the pump housing engagement pin 602 being hooked into the pump housing manual driver notch 222. As shown in FIG. 5C, pulling on the handle 611 extends the spring-loaded arm 601 allowing the handle 611 to rotate around the diameter of the pump housing engagement pin 602 such that the coupler slot engagement pin 612 aligns to the coupler slot 214a. As shown in FIG. 5D, the handle 611 is released causing the tension spring 616 (shown in FIG. 6A) to retract the spring-loaded arm 601 into the handle 611 pulling the coupler slot engagement pin 612 into the coupler slot 214a. The manual driver assembly is kept engaged in the two slots 214a, 222 by the tension spring 616 (shown in FIG. 6A) contained within the handle 611.

FIG. 6A is a cutaway perspective view showing the interior of the manual driver assembly 600 including the spring-loaded arm 601 (with pump housing engagement pin 602) and the handle 611 (with coupler slot engagement pin 612, stroke volume limiter pin 613, tension spring 616, and stroke volume limiter 621). The stroke volume limiter 621 has a stroke volume limiter finger grip 622 and three stroke volume limit indicator windows: the small stroke volume limit indicator window 623a, the medium stroke volume limit indicator window 624a, and the large stroke volume limit indicator window 625a.

FIG. 6B shows the manual driver assembly 600 including the spring-loaded arm 601 (with pump housing engagement pin 602) and the handle 611 (with coupler slot engagement pin 612, stroke volume limiter pin 613, stroke volume limiter spring 614, and stroke volume limiter 621). The cutaway interior view of the stroke volume limiter 621 shows the stroke volume limiter protrusion 615 and three stroke volume limit notches: the small stroke volume limit notch 623b, the medium stroke volume limit notch 624b, and the large stroke volume limit notch 625b.

FIGS. 7A-D & 8A-D show operation of the manual driver assembly 600 in a pumping sequence and of the function of the stroke volume limiter 621. Fluid flow during manual pumping is analogous to fluid flow during automated pumping, as more fully described in the applications bearing U.S. patent application Ser. Nos. 17/182,915, 17/182,893, 17/183,067, and 17/183,080.

FIGS. 7A-D are side perspective views of the pulsatile fluid pump apparatus 300 showing the manual driver assembly 600 attached to the integral pump assembly 200 which is mounted within the pulsatile fluid pump system 301 in the manual operating position.

FIGS. 7A (and 7C & 8A) shows the handle in the full up, or diastole, position with the stroke volume limiter 621 shown in the largest stroke volume limit position. As the handle 611 is raised, the integral pump assembly 200 experiences diastole mode just as if the push rod 342 (shown in FIGS. 11A-B) was pulled away from the integral pump assembly 200; the diaphragm 202 (shown in FIG. 8A) acts as a natural travel limiter to the upwards force. In this part of the stroke, the stroke volume limiter 621, regardless of setting, does not exert an influence, as it does not contact the pump housing 221.

FIGS. 7B (and 7D, 8C, & 8D) shows the handle in the full down, or systole, position. As the handle 611 is depressed, the integral pump assembly 200 experiences systole mode just as if the push rod 342 (shown in FIGS. 11A-B) was pushed towards the integral pump assembly 200. Shown in the largest stroke volume limit position, the stroke volume limiter 621 limits the amount of downward travel of the handle 611 by contacting the pump housing 221, which in turn limits the stroke volume delivered.

FIG. 7C is similar to FIG. 7A except the stroke volume limiter 621 is shown in the smallest stroke volume limit position. Similar to what is shown in FIG. 7A, in this part of the stroke, the stroke volume limiter 621, regardless of setting, does not exert an influence, as it does not contact the pump housing 221. In contrast with what is shown in FIG. 7A, it is apparent that there is less distance between the stroke volume limiter 621 and the pump housing 221, thus less travel of the handle 611, and thereby less fluid pumped.

FIG. 7D is similar to FIG. 7B except the stroke volume limiter 621 is shown in the smallest stroke volume limit position. As the handle 611 is depressed, the integral pump assembly 200 experiences systole mode just as if the push rod 342 (shown in FIGS. 11A-B) was pushed towards the integral pump assembly 200. Shown in the smallest stroke volume limit position, the stroke volume limiter 621 limits the amount of downward travel of the handle 611 by contacting the pump housing 221, which in turn limits the stroke volume delivered. In contrast with what is shown in FIG. 7B, when the stroke volume limiter 621 is in the smallest stroke volume limit position, it allows less overall travel of the handle 611 than when it is in the largest stroke volume limit position, thereby pumping less fluid.

FIGS. 8A-D are views of the manual driver assembly 600 attached to the integral pump assembly 200 in the manual operating position. For clarity, the manual driver assembly 600 and the integral pump assembly 200 are shown outside of the pulsatile fluid pump system 301. The diaphragm 202 within the integral pump assembly 200 is actuated by raising and lowering the handle 611 to effect manual pumping. The beat rate is determined by the frequency at which the operator pumps the handle 611.

FIG. 8A is a cutaway interior view of the manual driver assembly 600 attached to a vertical section of the integral pump assembly 200 in manual orientation in the diastole mode, with the stroke volume limiter 621 in the largest setting. The manual driver assembly 600 includes the spring-loaded arm 601 (with pump housing engagement pin 602) and the handle 611 (with coupler slot engagement pin 612 [shown in FIG. 8D], tension spring 616, and stroke volume limiter 621), and the stroke volume limiter protrusion 615. FIG. 8A further shows a vertical section of the integral pump assembly 200 wherein the diaphragm assembly 201 is mounted to a pump-valving assembly 101 in diastole mode, in which the chamber 102 is full.

The spring-loaded arm 601 is shown in the retracted position, pulled towards the handle 611 by the tension spring 616. The pump housing engagement pin 602 is seated in the pump housing manual driver notch 222 (shown in FIG. 8D), and the coupler slot engagement pin 612 (shown in FIG. 8D) is seated in the coupler slot 214a; the engagement pins 602, 612 (shown in FIG. 8D) are held in their respective slots 222 (shown in FIG. 8D), 214a by the tension exerted by the tension spring 616 pulling the handle 611 and spring-loaded arm 601 together.

Similar to what is shown in FIG. 7A, FIG. 8A shows the handle in the full up, or diastole, position. As the handle 611 is raised, the integral pump assembly 200 experiences diastole mode just as if the push rod 342 (shown in FIGS. 11A-B) was pulled away from the integral pump assembly 200; the diaphragm 202 (shown in FIG. 8A) acts as a natural travel limiter to the upwards force. The stroke volume limiter 621 is in the largest stroke volume setting as indicated by the relative position of the stroke volume limiter 621 to the stroke volume limiter protrusion 615, although

when in this part of the stroke, the stroke volume limiter 621 setting does not exert an influence, as it does not contact the pump housing 221.

FIG. 8B is a cutaway interior view of the manual driver assembly 600 attached to a vertical section of the integral pump assembly 200 in manual orientation, midway between the diastole and systole modes, with the stroke volume limiter 621 in the largest setting. The stroke volume limiter 621 is shown in the largest stroke volume, although when in this part of the stroke, the stroke volume limiter 621 setting does not exert an influence, as it does not contact the pump housing 221. The manual driver assembly 600 includes the spring-loaded arm 601 and the handle 611 (with stroke volume limiter 621). The integral pump assembly 200 has a diaphragm assembly 201 that is mounted to a pump-valving assembly 101, shown in mid-stroke (either systole or diastole) in which the chamber 102 is being either filled (diastole) or emptied (systole).

FIG. 8C is a cutaway interior view of the manual driver assembly 600 attached to a vertical section of the integral pump assembly 200 in manual orientation, in the systole mode, with the stroke volume limiter 621 in the largest setting. Similar to what is shown in FIG. 7B, FIG. 8C shows the handle in the full down, or systole, position with the stroke volume limiter 621 in the largest stroke volume setting, attached to the integral pump assembly 200 with the handle 611 in the systole position wherein the stroke volume limiter 621 is in contact with the pump housing 221, limiting further downward travel of the handle 611 and further compression of the diaphragm 202, thereby limiting the volume of fluid pumped.

FIG. 8C also shows a vertical section of the integral pump assembly 200 wherein diaphragm assembly 201 mounted to a pump-valving assembly 101 in systole mode, in which the chamber 102 is finished being emptied.

FIG. 8D is a view of the manual driver assembly 600 attached to a vertical section of the integral pump assembly 200 in manual orientation, in the systole mode, with the stroke volume limiter 621 in the smallest setting. Similar to what is shown in FIG. 7D, FIG. 8D shows the handle in the full down, or systole, position with the stroke volume limiter 621 in the smallest stroke volume limit position. The stroke volume limiter 621 limits the amount of downward travel of the handle 611 by contacting the pump housing 221, which in turn limits the stroke volume delivered. In this setting, the volume delivered is less than in FIG. 8C. The integral pump assembly 200 has a diaphragm assembly 201 mounted to a pump-valving assembly 101, shown in systole mode in which the chamber 102 is being emptied.

FIG. 8D shows the manual driver assembly 600 including the spring-loaded arm 601 (with pump housing engagement pin 602) and the handle 611 (with coupler slot engagement pin 612 and stroke volume limiter 621 with stroke volume limiter finger grip 622). The spring-loaded arm 601 is shown in the retracted position, pulled towards the handle 611 by the tension spring 616 (not shown). The pump housing engagement pin 602 is seated in the pump housing manual driver notch 222, and the coupler slot engagement pin 612 is seated in the coupler slot 214a; the engagement pins 602, 612 are held in their respective slots 222, 214a by the tension exerted by the tension spring 616 (not shown) pulling the handle 611 and spring-loaded arm 601 together.

FIG. 9 shows a graphic display 400 mounted in the pulsatile fluid pump 301.

As shown in FIG. 10, the graphic display 400 may show a set of flow-based attributes (a subset of physical flow characteristics), such as beat rate 401b, average flow rate

411a, stroke volume **411b**, flow rate index **411c**, the flow rate waveform **412**, and/or the stroke volume waveform **413**, as operator actuates the integral pump assembly **200** (shown in FIG. 9) via by the manual driver assembly **600** (not shown).

FIG. 11A is a vertical section of the pulsatile fluid pump apparatus **300** of FIG. 1 including the pulsatile fluid pump system **301** and the integral pump assembly **200**. The pulsatile fluid pump system **301** includes, among other things, a linear motor **330**, push rod assembly **341** (comprised of a push rod **342** and force sensor **372**), control housing **361**, and chassis **363**. The integral pump assembly **200** (comprised of, among other things, a pump-valving assembly **101**, with chamber **102**, diaphragm assembly **201**, and peripheral flange **221a**), mounted in the normal operating position, is held by the peripheral flange **221a** and compliant member (not shown) in the channel **362** within the control housing **361** of the pulsatile fluid pump system **301**.

FIG. 11B is a vertical section of the pulsatile fluid pump apparatus **300** of FIG. 1 including the pulsatile fluid pump system **301** and the integral pump assembly **200**. The pulsatile fluid pump system **301** consists of, among other things, a linear motor **330**, push rod assembly **341** (comprised of a push rod **342** and force sensor **372**), control housing **361**, and chassis **363**. An integral pump assembly **200** (comprised of, among other things, a pump-valving assembly **101** with chamber **102**, diaphragm assembly **201**, and peripheral flange **221a**), mounted in the manual operating position, is held by the peripheral flange **221a** and compliant member **221c** (not shown) in the channel **362** within the control housing **361** of the pulsatile fluid pump system **301**. The manual driver assembly **600** (comprised of, among other things, the spring-loaded arm **601**, pump housing engagement pin **602**, and handle **611**) is shown attached to the integral pump assembly **200**.

The pulsatile fluid pump system **301** is an ideal platform for manual operation of the integral pump assembly **200** utilizing the manual driver assembly **600** as: (a) the integral pump assembly **200** remains in a nearly spatial location regardless of whether the integral pump assembly **200** is in the normal operating position (FIG. 11A) or the manual operating position (FIG. 11B), thereby minimizing the need for the operator to reroute tubing, etc.; and (b) the mass of pulsatile fluid pump system **301** provides the necessary counter-acting force when the handle **611** is used to operate the integral pump assembly **200**.

FIGS. 12A D show a second embodiment of a manual driver assembly in accordance with the present invention. Although this embodiment lacks the mechanical advantage of the aforementioned manual driver assembly **600** (not shown), it is far simpler, being a manual driver knob assembly **690** which connects to the coupler slot **214a** of the diaphragm assembly **201** by sliding the manual driver knob T-stem into the coupler slot **214a**. The diaphragm assembly **201** is actuated by repeatedly pushing and pulling on the manual knob handle **691** relative to the integral pump assembly **200**.

FIG. 12A shows a perspective view of the manual driver knob assembly **690**, in accordance with an embodiment of the present invention, including a manual driver knob handle **691** attached to a manual driver knob T-stem **692**.

FIG. 12B shows a front view of the manual driver knob assembly **690** of FIG. 12A, including the manual driver knob handle **691** attached to the manual driver knob T-stem **692**.

FIG. 12C shows the manual driver knob assembly **690** of FIG. 12A (comprised of manual driver knob handle **691**

attached to a manual driver knob T-stem **692**) immediately prior to attachment to the diaphragm assembly **201** via the coupler slot **214a**. The integral pump housing **200** is in the manual operating position so that the manual driver knob assembly **690** may be attached to the diaphragm assembly **201** by sliding the manual driver knob driver T-stem **692** into the coupler slot **214a**.

FIG. 12D shows the manual driver knob assembly **690** of FIG. 12A (comprised of manual driver knob handle **691** attached to a manual driver knob T-stem **692**) after attachment to the diaphragm assembly **201** via the coupler slot **214a**, ready for manual pumping. The integral pump housing **200** is in the manual operating position. The manual driver knob driver T-stem **692** is inside the coupler slot **214a**. The diaphragm assembly **201** is actuated by pushing and pulling on the manual knob handle **691** relative to the integral pump assembly **200**. The pump may be manually operated by holding the integral pump assembly **200** in one hand and grasping the manual driver knob handle **691** with the other, or by mounting the integral pump assembly **200** within the pulsatile fluid pump system **301** in the manual operating position and then actuating the manual driver knob handle **691** with one hand.

The embodiments of the invention described above are intended to be merely exemplary; numerous variations and modifications will be apparent to those skilled in the art. All such variations and modifications are intended to be within the scope of the present invention as defined in any appended claims.

What is claimed is:

1. A pulsatile fluid pump apparatus comprising: an integral pump assembly employing a flexible dia-

phragm in a diaphragm assembly;

a manual driver assembly; and

a pulsatile fluid pump system including a control housing; the control housing and the integral pump assembly being configured for operation:

in a first mode, wherein the integral pump assembly is coupled to the control housing and the pulsatile fluid pump system reciprocally actuates the diaphragm assembly to cause pumping automatically, and

in a second mode, wherein the integral pump assembly has been nondestructively removed from the control housing in a manner to expose the diaphragm assembly, the manual driver assembly configured to be coupled to the diaphragm assembly so that manipulation of the manual driver assembly reciprocally actuates the diaphragm assembly to cause pumping.

2. A pulsatile fluid pump apparatus according to claim 1, wherein the integral pump assembly is configured to operate in any spatial orientation.

3. A pulsatile fluid pump apparatus according to claim 1, wherein, for operation in the first mode, the diaphragm assembly has a normal orientation in the control housing so as to be in contact with a pushrod assembly to cause reciprocation of the flexible diaphragm.

4. A pulsatile fluid pump apparatus according to claim 1, wherein the integral pump assembly is configured to slide into and out of the control housing.

5. A pulsatile fluid pump apparatus according to claim 3, wherein the integral pump assembly is configured, in the second mode, to be in an inverted orientation in the control housing relative to the normal orientation of the diaphragm assembly, so as to expose the diaphragm assembly for convenient attachment of the manual driver assembly and wherein the pulsatile fluid pump system is not operationally

connected to the integral pump assembly and therefore does not cause reciprocation of the diaphragm assembly.

6. A pulsatile fluid pump apparatus according to claim **5**, wherein the control housing is configured to receive and hold the integral pump assembly in the inverted orientation. ⁵

7. A pulsatile fluid pump apparatus according to claim **1**, wherein (i) the manual driver assembly includes an arm configured to be pivotally mounted to a housing of the integral pump assembly and (ii) the arm is coupled to a handle having a foot that reciprocally moves the diaphragm ¹⁰ assembly when the handle is pumped.

8. A pulsatile fluid pump apparatus according to claim **1**, wherein the manual driver assembly is a knob assembly.

9. A pulsatile fluid pump apparatus according to claim **7**, wherein the manual driver assembly includes a stroke volume limiter, disposed between the handle and the foot, and configured to limit, by an adjustable amount, a change in stroke volume effectuated by the manual driver assembly. ¹⁵

10. A pulsatile fluid pump apparatus according to claim **9**, wherein the stroke volume limiter defines a plurality of ²⁰ notched orientations, each orientation establishing a distinct limit on travel of the manual driver assembly.

11. A pulsatile fluid pump apparatus according to claim **1**, wherein the pulsatile fluid pump system has an integral storage location for stowing the manual driver assembly ²⁵ when it is not being used.
